F. B. DISCO

COMBUSTION TUBE

Filed Dec. 29, 1924

Inventor
Frank B. Disco

By

A. Bradford
Attorney

UNITED STATES PATENT OFFICE.

FRANK B. DISCO, OF NORWICH, CONNECTICUT.

COMBUSTION TUBE.

Application filed December 29, 1924. Serial No. 758,745.

To all whom it may concern:

Be it known that I, FRANK B. DISCO, a citizen of the United States, residing at Norwich, in the county of New London and

5 State of Connecticut, have invented certain new and useful Improvements in Combustion Tubes, of which the following is a specification.

10 My said invention relates to a combustion tube for stoves and furnaces designed to be applied in the smoke outlet pipe thereof and adapted to be shifted to constrict the outlet for smoke thereby serving as a damper.

15 It is an object of the invention to provide a device of this character which will produce a more complete combustion of the fuel and also a more thorough combustion of the gases generated from the fuel during

20 the burning operation.

Another object of the invention is to provide an inexpensive and simple device which may be readily adapted to the conventional stove pipe.

25 Referring to the accompanying drawing, which is made a part hereof and on which similar reference characters indicate similar parts—

30 Figure 1 is a side elevation partly in section of a furnace having my invention applied thereto.

Figure 2 is a fragmentary sectional view showing a modified form of valve.

In the drawings reference character 10 35 indicates a furnace of the usual hot air type having a feed door 11 and ash pit door 12 with a smoke outlet pipe 13 extending into a chimney 14. Mounted concentrically of the smoke pipe 13 is a tube 15 secured there- 40 in by means of supporting elements 16 and having at its outer end an annular radially extending flange 17 forming a valve head adapted to be shifted by means of the operating lever 19 to bring said valve head into 45 contact with the end of the pipe or valve seat 18 of the pipe 13.

The tube 15 is mounted so as to move longitudinally through the supporting elements 16 and is adapted to be shifted from the position shown to the dotted line position by the operating lever. In the position shown the smoke from the furnace will readily pass out around the small tube 15 and up the chimney flue, however, when the 50 tube 15 is shifted to the dotted line position illustrated the valve head 17 will con-

tact or seat on the pipe end 18 closing the annular passage around the same and permit only a small volume of smoke to pass out through the tube 15. 60

In order to insure a more thorough and complete combustion of the fuel utilized in the furnace and to cause the gases escaping with the smoke to be more thoroughly consumed I provide a draft or air inlet 20 65 substantially toward the rear end of the combustion tube by means of which air may enter the smoke pipe and be partially heated as it passes around the tube toward the front end thereof where it may readily commingle with the gaseous products escaping from the fuel and as a result thereof said gaseous products will be practically entirely consumed by the fire in the furnace. 70

It will be seen from the foregoing that 75 the combustion tube may be readily applied to smoke pipes of different sizes without varying the construction of the same by merely providing supporting elements of a size to correspond with the internal size of 80 the pipe to which the same is applied. It will also be noted that the combustion tube may be cheaply constructed of sheet metal and the thinner the tube the more thoroughly 85 the incoming air will be heated.

It will be obvious to those skilled in the art 90 that changes may be made in my device without departing from the spirit of the invention and therefore I do not limit myself to the precise construction shown in the drawings and described in the specification but only as indicated in the appended claims.

While in Figure 1 I have shown the valve 17 as a flat disk adapted to impinge closely against the end of pipe 13 it will be understood, of course, that other forms may be used without departing from my invention; for example, in Figure 2 I have shown a modified construction wherein the valve is of conical form and I have provided an internal flange or bead 21 on the inner surface of the pipe 13 at its end against which said valve may seat. Such construction may be preferred in some instances or even other forms, it being understood that my invention is only limited in this and other particulars by the terms of the claims. 100

Having thus fully described my said invention, what I claim as new and desire to secure by Letters Patents, is:

110 1. In combination with a furnace, a smoke outlet pipe, a concentrically mounted tube

extending longitudinally thereof, a radially extending flange on the outer end of said tube, and means for moving said flange into engagement with the end of said smoke outlet pipe, substantially as set forth.

2. In combination with a furnace having a fire pot, a smoke outlet pipe extending from said fire pot, a tube supported concentrically of said smoke pipe and terminating adjacent the upper end of said fire pot, an annular radially extending flange at the outer end of said tube of a diameter greater than the inside diameter of the smoke pipe, means for moving said flange against the end of the smoke pipe, an air inlet in said smoke pipe intermediate the ends thereof for permitting air to pass into said smoke pipe around said combustion tube to said fire pot and through said combustion tube, substantially as set forth.

3. In combination with a furnace having a fire pot, a smoke outlet pipe extending from said fire pot, a tube supported concentrically of said smoke pipe and terminating adjacent the upper end of said fire pot, an annular radially extending flange at the outer end of said tube of a diameter greater than the inside diameter of the smoke pipe said tube being longitudinally movable in said smoke pipe, means for moving said tube to seat the annular extending flange against the end of the smoke pipe, an air inlet in said smoke pipe intermediate the ends thereof for permitting air to pass into said smoke pipe around said combustion tube to said fire pot and through said combustion tube, substantially as set forth.

4. A combustion tube for smoke outlet pipes for furnaces having an annular ra-

dially extending flange at one end thereof for engagement with the end of the smoke pipe and means for moving said flange against the end of said pipe to cause the smoke to pass through said tube and for spacing the same from the end of said pipe for permitting the smoke to pass out around said tube, substantially as set forth.

5. In combination with a furnace, a smoke outlet pipe, a concentrically mounted tube extending longitudinally thereof, a radially extending flange on the outer end said tube, an air inlet in said smoke pipe intermediate the end thereof, means for moving said tube longitudinally of said smoke pipe to cause said flange to contact the end of the smoke pipe whereby air will be drawn in through the air inlet and will be heated and mingled with the gases in said furnace, substantially as set forth.

6. In combination with a furnace a smoke outlet pipe, a concentrically mounted tube extending longitudinally thereof and having a radially extending flange around its outer end adapted to be moved into engagement with the end of said smoke pipe, a handle pivoted to said tube and extending through said smoke pipe for moving the tube longitudinally of said pipe and a damper intermediate the ends of said smoke pipe, substantially as set forth.

In witness whereof, I have hereunto set my hand and seal at Norwich, Connecticut this 26th day of December, A. D. nineteen hundred and twenty-four.

FRANK B. DISCO.
